UNITED STATES PATENT OFFICE.

LOUIS N. UDELL, OF ST. LOUIS, MISSOURI.

PAPER-FASTENER.

1,164,685.

Specification of Letters Patent. Patented Dec. 21, 1915.

Application filed January 30, 1915. Serial No. 5,176.

To all whom it may concern:

Be it known that I, LOUIS N. UDELL, a citizen of the United States, residing at St. Louis, in the State of Missouri, have invented certain new and useful Improvements in Paper-Fasteners, of which the following is a specification.

This invention relates to paper fasteners and has reference more particularly to fasteners of the pin type.

The object of the invention is to provide an improved fastener which shall be capable of use with an ordinary pin, which shall render the use of an ordinary pin entirely safe, as to the possibility of injury therefrom, both while inserting the pin and after it is in place, which shall increase the capacity of a pin of any given size over its capacity as ordinarily used, which shall, when applied, be positively fastened to the paper instead of merely gripping the same by a spring clamping action, which may be easily applied and as easily removed, which shall be reusable, and which shall require no tool for applying or removing the same.

To this end my invention resides in a paper fastener having novel features of structure and mode of manipulation substantially as hereinafter described and pointed out in the claims.

The device of my invention in the preferred mechanical embodiment thereof, is illustrated in the accompanying drawing, in which—

Figure 1 is a fragmentary view showing in perspective one corner portion of a group of superposed sheets of paper secured together by my improved fastener; Fig. 2 is a perspective elevation of the U-shaped clip of the fastener; Fig. 3 is a perspective plan view of a partially formed blank from which the U-shaped clip is made; Fig. 4 is an enlarged longitudinal section on the line 4—4 of Fig. 1; Fig. 5 is an enlarged cross section on the line 5—5 of Fig. 1.

The device of my invention consists of two principal members; an ordinary pin or similar pointed instrument, and a generally U-shaped clip formed of thin sheet metal that embraces an edge of the papers to be bound together and co-operates with said pin, in the manner hereinafter described, to securely fasten the papers against separation otherwise than by withdrawal of the pin or tearing of the paper.

Referring to the drawing, 6 designates

the lower limb, and 7 the upper limb of the generally U-shaped clip, which latter may conveniently be bent to shape from a sheet metal blank similar to that shown in Fig. 3. Said blank, which is preferably cut from some thin sheet metal such as tin or brass, is formed with a lateral wing 8 on one edge of the lower limb 6, which wing is bent over the upper surface of the limb 6, its free edge 9 being bent beneath the opposite edge of the limb 6, as clearly shown in Fig. 5, thereby forming between the lower limb 6 and the folded wing 8 a flat pocket to receive the fastening pin hereafter referred to. The lower limb 6 is also preferably formed with a longitudinal groove or channel 10 in its upper surface that co-operates with the covering member 8 in forming the pocket and also serves as a guide for the point of the pin when being introduced to the pocket. The metal blank is further formed with a transverse groove or depression 11 constituting a portion of slightly greater flexibility than the main limb portion, so that the blank will readily bend thereon in folding.

The upper limb 7 which, as herein shown, may be somewhat narrower than the lower limb 6, is provided at its free end with a hole 12 through which an ordinary pin 13 is adapted to be inserted. To facilitate the introduction of the pin through the bunch of paper sheets and into the pocket, the metal inwardly of the hole 12 (or in the direction of the folded end) is slightly upset as shown at 14, while the metal on the opposite or outer side of the hole is depressed as shown at 15.

To apply the fastener, the metal clip is inserted over one edge of a group of superposed paper sheets such as are indicated at 16, and an ordinary pin 13 is passed through the hole 12 and forced through the paper mat, its pointed end striking the guide-groove or channel 10 in the lower limb of the device. Under continued pressure on the head of the pin, the point of the pin slides down the groove 10 beneath the cover 8 and into the pocket formed by and between said parts, until occupying the working position substantially shown in and by Fig. 4. In this operation, the fingers of the user are fully protected against being pricked by the sharp point of the pin by the lower limb 6 of the clip which acts as a shield. When the pin is in place the clip cannot be moved in any direction without tearing the paper.

It will further be noted that the action of the pin when entering this guide and pocket is such as to cause a clamping effect, equal to the bending strength of the pin, between the upper and lower limbs of the clip, all tending to hold the paper sheets tightly together.

From the foregoing description and the accompanying illustration it will be readily seen how the device of my invention effects the stated object and advantages. The use of the covering member 8 on the lower limb of the clip to form the upper wall of the pin pocket is preferred, since it co-operates with the pin to produce the clamping action above mentioned; but this covering member may be omitted and the guide-groove alone be employed, in a somewhat simpler form of the invention, since the presence of the guide-groove will insure the piercing of the entire bunch of papers by a pin.

While I have described the invention as a paper fastener and contemplate that such will be its principal application and use, it will be manifest that it might to advantage be applied as a fastener for various other materials without involving any change in structure, principle, or substantial utility.

I claim:

1. A two-piece paper fastener, comprising a generally U-shaped clip adapted to embrace an edge portion of a plurality of superposed sheets, the lower limb of said clip having on its inner face a longitudinal groove forming a guide for the pointed end of a pin, and the upper limb having a hole at its free end, and a separable pin having a body portion adapted to slidingly engage

said hole and guide groove and pierce the sheets therebetween and a head adapted to abut against the outer side of the free end of the upper limb over said hole.

2. A two-piece paper fastener, comprising a generally U-shaped clip adapted to embrace an edge portion of a plurality of superposed sheets, the lower limb of said clip having on its inner face a pocket the side walls of which extend lengthwise of said lower limb, and the upper limb having a hole at its free end, and a separable headed pin the body portion of which is adapted to pass through said hole and enter said pocket and pierce the sheets therebetween, thereby drawing the two limbs of said clip together on said sheets.

3. A two-piece paper fastener, comprising a generally U-shaped thin metal clip adapted to embrace an edge portion of a plurality of superposed sheets, the lower limb of said clip being formed on its inner face with a depressed longitudinal guide groove and further provided with an integral covering member forming with said guide groove a pocket extending lengthwise of said lower limb, and the upper limb having a hole at its free end, and a separable headed pin the body portion of which is adapted to pass through said hole and enter said pocket and pierce the sheets therebetween, whereby the two limbs of the clip are clamped together on said sheets.

L. N. UDELL.
